WORKBOX FOR SEWING MATERIAL AND
TAILOR TOOLS

Per Jack Rohde, Oslo, Norway

Application January 23, 1950, Serial No. 140,117
In Norway January 29, 1948

1 Claim. (Cl. 223—106)

1

The present invention relates to a work box for sewing material and tailor tools intended to replace the so-called tailor boxes, in which the materials and tools, used by the tailors, are placed without any order. These tailor boxes, besides being unpractical and preventing a rational work, are also unhygienic, as they easily accumulate dust and other contaminations.

The main characteristic feature of the invention is that said work box consists of two side walls, which are interconnected at their lower part by means of a list frame, in which is placed a wire-gauze serving as bottom, on which buttons and the like are placed. The side walls are at their upper part interconnected by means of a suitable number of cross-bars, which are placed stepwise above and behind each other and provided with holes for detachable fastening of a number of vertical pins for placing of cotton reels and spools.

A further feature of the invention is that the outer side of one of the side walls of the work box is provided with an oblique channel intended to hold a pair of scissors, whereas the inner side of the opposite side wall is provided with two oblique channels adapted to hold a pencil and a bodkin. Further, on the inner side of one of the side walls is placed a preferably oblique pin cushion, while the inner side of the opposite side wall carries a small box for the chalk.

One embodiment of the invention is shown on the accompanying drawing, in which:

Figure 1 is a front view of the work box, and

Figure 2 is a side view of the box seen from the side situated to the right in Figure 1.

The work box consists of two side walls 1 and 2, which at their lower part are interconnected by means of a list-frame consisting of two halves 3, 4 and 3₁, 4₁, which are interconnected and placed above each other, the frame bars 4, 4₁ of which being fastened to the inner side of the side walls 1, 2, while the frame bars 3, 3₁ from the crosswise connection between the side walls. The front and the rear of the work box are open. The work box, however, is provided with a bottom 5, on which buttons and the like may be placed. The bottom is made of wire-gauze, so that dust and the like easily may fall through. The wire-gauze is jammed between the frame halves 3, 4 and 3₁, 4₁, so that the upper frame half 3₁, 4₁ forms a vertical flange around the wire-gauze.

The upper parts of the side walls are inter-

2

connected by means of cross-bars 6, which are arranged stepwise above and behind each other close below the oblique and preferably curved upper edge of the side walls. Said bars are provided with a number of holes for detachable fastening of vertical pins 7 intended to hold cotton reels and/or spools.

In order to have the scissors at hand at any time, the outer side of the right side wall 1 is provided with a somewhat oblique channel 9 limited by the walls 8, in which the scissors are placed when not in use. Further, the inner side of the left side wall 2 is provided with two oblique channels 16 and 17 limited by the walls 15, in which pencil and bodkin may be placed.

The inner side of the side wall 2 is also provided with a box limited by the walls 12, said box serving as a container for the tailor chalk. The upper part of the walls of this box is provided 20 with suitably formed incisions 14, so that the chalk may easily be gripped. Further, the inner side of the side wall 1 is provided with a wood piece or the like 11, the upper side of which is oblique and on which is placed an oblique pin cushion 10. The foremost edge of the wood piece 11 is suitably resting on the foremost frame bar 4₁.

The constructive details of the invention also may be carried out in many other ways without departing from the scope of this invention.

30 I claim:

A work box for tailors for the placing of sewing materials and tools, characterized thereby that the box consists of two side walls being at their lower part interconnected by means of a list frame, in which is placed a bottom of wire-gauze, on which are to be placed buttons and the like, said side walls at their upper part being interconnected by means of a suitable number of cross-bars placed step-wise above and behind each other, which cross-bars are provided with holes for detachable fastening of a suitable number of vertical pins for placing of cotton reels and/or spools.
